OSCILLATING CYLINDER FLAT BED VARIABLE SHEET PRINTING PRESS

Paul F. Cox, Chicago, Ill.

Application March 27, 1939, Serial No. 264,454

24 Claims. (Cl. 101—258)

This invention is an improvement in bed and cylinder web perfecting presses of the type shown in my companion application for Stop cylinder vertical reciprocating flat bed presses, filed December 27, 1938, Serial No. 247,932.

The principal objects of this invention are to provide a press which can print webs from flat type forms, and produce products of variable lengths of sheets. The press has oscillating impression cylinders having gears meshing with racks on movable flat type beds; the cylinders are thrown on impression during the printing operation and off impression after such operation and during the return strokes of the beds. The web is fed in and fed out during the taking of impressions and stopped after the impressions are taken and during the nonimpression strokes of the beds, while the cylinders are off impression. The cutting cylinders may be driven continuously, and make one complete revolution for each reciprocation of the beds. The feed and delivery rolls are actuated to forward the web during the taking of impressions, and novel means is provided whereby the length of web fed during the taking of impressions may be varied, so that sheets of any desired length (between minimum and maximum) may be printed as desired; this capacity for variable size product greatly enhances the utility and value of the press.

Other minor objects and novel features of the invention will be hereinafter referred to in the detailed description of the press illustrated.

The press will produce good clean-cut impressions on hard-finished or book paper, and is especially adapted for small printing offices which need a roll-feed web press that will be less expensive and produce a better grade of work than can be printed on the flat bed web presses now on the market.

In the accompanying drawings I have illustrated one practical embodiment of the invention in a perfecting press, and will describe the same with reference thereto, and those familiar with the art will readily understand and appreciate its practicality and advantages. The press shown is a perfecting press, but it might be constructed with but one bed and cylinder and if it is to be used only for non-perfected work, but if constructed as a perfecting press it can be used as a non-perfected job press by leading the web only between one bed and cylinder. The claims set forth the essential features of the invention and various novel features of construction, and

novel combination of parts, for which protection is desired.

In said drawings—

Fig. 1 is a side elevation of the press, partly broken away.

Fig. 2 is an end elevation of the press.

Fig. 3 is a top plan view of the press.

Fig. 4 is a horizontal sectional view of part of the press on line 4—4, Fig. 1.

Fig. 5 is an enlarged detail illustrating the clutch drive for the feed roll.

Fig. 6 is a detail view of the clutch operating devices.

Fig. 7 is a diagrammatic longitudinal section of the press, showing the path of the web, and in-feed, out-feed devices, and cutting cylinders.

The press shown comprises two vertically disposed oppositely outwardly facing type beds 1 and 2 connected by cross bars 3 which hold the beds rigidly together and in sliding engagement with vertically disposed guides 3a on the side frames of the press (see Figs. 1 and 4). The beds may be reciprocated vertically by means of pitmen 4 pivotally connected to the outer ends of a shaft 4a, that extends between the beds and through the bars 3, and to crank pins on wheels 4b fixed on a transverse shaft 4c journaled in bearings in the side frames of the press and disposed vertically above and parallel with shaft 4a. (See Fig. 1.)

One of the wheels 4b (see Fig. 2) is shown as provided with gear teeth that mesh with a pinion 4d on a stub shaft 4e, journaled in the adjacent side frame of the press and a bracket 4f attached thereto, see Figs. 2 and 3. On stub shaft 4e is a pulley 4g which may be driven by a belt from any suitable driver (not shown).

The beds are preferably counterbalanced. As shown an oppositely movable weight 1x is connected to bed 1 by chains 1y running over pulleys 1z mounted on a shaft journaled in the frame of the press above shaft 4c. Similarly bed 2 is counterbalanced by a weight 2x connected to the bed by chains 2y running over pulleys 2z on a shaft mounted on the frame of the press. The counterbalancing weights may be guided by and between the beds, as indicated in Figs. 1 and 3.

Cooperating with bed 1 is an impression cylinder 6, having a gear 6b meshing with a rack 1s on bed 1. The cylinder is actuated by the movement of the bed, and turns in one direction during the printing stroke of the bed, and in the reverse direction during the return stroke of the bed. The cylinder is thrown off impression at the end of the printing operation and during

the return stroke of the bed, and is thrown on impression at the beginning of the printing stroke of bed. The cylinders may be thrown on and off impression by any suitable means, but in the combination shown I use a novel means, as follows: The cylinder 6 is rotatably mounted on a shaft 6s which has eccentric trunnions 6r fixed on its ends journaled in the side frames of the press (Figs. 1, 4 and 7). On one trunnion is a lever 6t which is normally depressed by a spring 6u (Fig. 1) and is connected by rod 6v to one arm of a three-armed lever 6w pivoted on the adjacent side frame. Another arm of lever 6w carries a pin or roller 6x which is engaged at the proper time by a cam 4t on the adjacent wheel 4b (see Fig. 2), which cam at the proper time actuates the lever 6w and through the described connections rocks shaft 6s and throws and holds cylinder 6 off impression until the next printing operation is to begin, at which time the cam disengages roller 6x and spring 6u thus causes lever 6t to rock shaft 6s and throw the cylinder on impression.

Cooperating with bed 2 is an impression cylinder 7 having a gear 7b meshing with a rack 2s on bed 2. Cylinder 7 is rotatably mounted on a shaft 7s (Fig. 4) which carries eccentric trunnions 7r journaled in the frame. To one trunnion is attached a lever 7t (Fig. 1) which is connected by a rod 7u to the third arm 6y of lever 6w, so that when said lever is rocked by cam 4t or spring 6u cylinder 7 will be thrown off or on impression like, and simultaneously with, cylinder 6.

35 The cam on wheel 4b is preferably made in two sections 4s and 4t. Part 4t is fixedly attached to wheel 4b and its forward end engages the roller 6x at the beginning of the printing strokes of the beds and causes lever 6w to throw the cylinders on impression. Part 4s of the cam is adjustably attached to the wheel 4 and constitutes an adjustable extension of part 4t. The object of this extensible cam construction is to regulate and permit variation in the length of sheet fed and printed during a cycle of operations of the press. When section 4s is adjusted to extend the cam 4t, 4s to its greatest length the longest sheet will be fed and printed. When part 4s is adjusted to make the cam (4t-4s) shortest, then the shortest length sheet will be fed and printed. Intermediate adjustments of the length of cam can be made to enable any desired length of sheet (between the minimum and maximum lengths for which the press is designed) to be fed and printed.

55 The adjustable cam 4t-4s may be of any desired construction, capable of effecting the object stated; and be attached to the wheel 4b in any suitable or preferred manner. Section 4t might be made integral with the wheel if desired.

60 The web w is fed from a roll W and directed, successively, to the infeed roll, the first impression cylinder, the second impression cylinder, the out feed roll, and the cutting cylinders as follows, see Figs. 1 and 7.

65 The web w passes from roll W to and over a guide a; thence down under a looping roller 16, then up to and over a guide b, then down to and under a guide c; then to and under a guide d, thence up to a guide e below shaft 4c; then to the feed roll 11; thence to and over a guide f, and down to a guide g adjacent and above cylinder 6; then down to and under a guide h below the cylinder. The guides g, h, enable the impression cylinder 6 to present the web to bed 1,

where it receives the first impression. The web passes from guide h out under cylinder 6 to a guide i, from which it passes up to and over a guide j; thence it passes above the in-feed roll 11 to a guide k and thence down to a guide m above cylinder 7, and down to a guide n below cylinder 7; said guides m, n, enabling cylinder 7 to present the web to the type bed 2 and make the perfecting impression on the web.

70 The tension of the web between the cylinders 6 and 7 is regulated by the guide j, which is mounted in swingable arms 27 which can be adjusted by hand screw 27a. The register of the impressions can also be regulated by adjusting guide j. If it should be desired to deliver the 15 web after it is printed on one side by cylinder 6 and bed 1, the web might be led from guide k direct to guide o and thence to the out-feed roll 12.

75 In the construction shown the looping roller 16 is a gravitational roller and is mounted in swingable arms 16a attached to a stub shaft 16b having an arm 16c connected by a rod 16d to the control lever 16e of an automatic brake 16f on the shaft 16z carrying the web roll. When roller 16 drops 25 to low position (Fig. 1) it applies the brake. When the in-feed roll is actuated it tends to draw web from the loop around roller 16 and as the latter rises it releases the brake and roll W begins to unwind and continues unwinding until 30 after the printing operation and roller 16 has again descended to brake applying position. The construction of the brake mechanism shown is well known. Any other suitable type might be used. 35

40 The in-feed roll 11 is rotatably mounted on the shaft 4c and with it cooperate tapes 11a running over guide rollers 11b, 11c and 11d. Roller 11d is preferably mounted in swinging levers 11e which can be adjusted by hand screw 11f to tension the tapes as desired.

45 The out-feed roll 12 is shown as driven from the cylinder 7, so that it is operated only when said cylinder is printing or on impression. The out-feed roll 12 has coacting tapes 12s running over rollers 12t, 12u. Roller 12t is mounted on swingable arms 12v which can be adjusted by hand screw 12w. As shown (see Figs. 2, 5 and 6) cylinder 7 has a gear 7j on one end meshing with a gear 17 on a shaft 17a parallel with and 50 above cylinder 7. Gear 17 is loose on shaft 17a and is engaged by a collar 17e slidably connected by pins 17f to a sleeve 17g rotatably mounted on a threaded sleeve 17i fixed concentric to shaft 17a. On shaft 17a beside gear 17 is fixed a sprocket 55 17b. The hubs of this sprocket and of gear 17 are provided with opposed clutch faces or devices (as at 17d, Fig. 5) whereby they will be interlocked when gear 17 is moved toward sprocket 17b; and unlocked when gear 17 moves away 60 from sprocket 17b. Any suitable clutch may be used. Springs may be strung on the pins 17f as in Fig. 5 to cushion the shock of engagement of the clutch.

65 Sleeve 17g has an arm 17h connected by a link 17k to an arm 17m fixed on the eccentric shaft 7s on which cylinder 7 is mounted (Figs. 5 and 6). Consequently when shaft 7s is rocked arm 17m through link 17k will turn sleeve 17g, and the threaded engagement of sleeve 17g with 17i will 70 cause sleeve 17g to move endwise on shaft 17a, and move gear 17 toward sprocket 17b and engage the clutch. Sprocket 17b and shaft 17a will then be rotated as long as the cylinder 7 is on impression. When cylinder 7 is thrown off impression 75

sion gear 17 will be moved away from sprocket 17b and the clutch disengaged. Sprocket 17b and the shaft 17a will be idle.

As shown, the out-feed roll 12 is provided with a sprocket 12a driven by a chain 12b from the sprocket 17b on shaft 17a, so the out-feed is actuated only when the cylinders are on impression.

In the construction shown the in-feed roll is driven from the out-feed roll. The in-feed roll 11 carries a gear 11m (Fig. 3) which meshes with a pinion 11o on the shaft 11n on which rollers 11c are mounted. The shaft 11n has a sprocket 11p driven by a chain 11q from a sprocket on the 15 out-feed roll shaft (Fig. 3).

The out-feed web is directed from the out-feed roll to cutting cylinders 18, by usual guides 19. The cutting cylinders are rotated once for each cycle of operations of press (which occurs 20 once for and during each revolution of shaft 4c). As shown the cutting cylinders may be directly driven from shaft 4c by a sprocket chain 18c running over a sprocket 18d on the upper cutting cylinder shaft, and over a sprocket 4p on shaft 4c.

25 The bed 1 is supplied with ink from an inking mechanism mounted in section A below cylinder 6. The inking mechanism may be of any suitable construction. As shown it comprises a fountain 8, ductors 8a, a set of distributing rollers 8b, with 30 proper adjusting and actuating mechanism, and two form rollers 8c. The particular inking mechanism used is not a feature of the present invention, and therefore further description thereof is unnecessary.

35 The bed 2 is also supplied with ink from a similar inking mechanism mounted in section C of the press, including a fountain 9, ductor 9a, distributing rollers 9b, and two form rollers 9c. In my press I am able to use two form rollers with 40 resultant enhanced clearness and uniformity of impressions.

The web is fed through the press by the co-operation of the cylinders with the forms on the moving beds aided by the in-feed roll 11 and the 45 out-feed roll 12. The first cylinder and bed advance the web to the second cylinder and bed, and the latter advance it to the out-feed roll 12. In my stop cylinder press above referred to the circumference of the impression cylinders 50 determines the length of sheets to be severed. In the present invention the impression cylinders may be of any desired size, as the length of sheets printed are not dependent upon the circumference of the cylinders; and the latter can 55 be made large enough to provide ample room for the blanket reels in the cylinder. The impression cylinders are easily accessible for make ready and packing, and overlays can be readily placed on either cylinder.

60 The fountains and inking mechanisms disposed below the cylinders are easily accessible. The web does not have to pass around either fountain. The plurality of form rollers employed enhances the quality of the impressions. The 65 quality of the product is also enhanced by the fact that the printed sides of the web does not contact with any guide or looping roller.

If desired the press frames may be made in sections A, B, C, and the operative parts assembled therein, as described in my aforesaid companion application, and the assembled sections shipped to purchaser and set up in situ.

70 The web is intermittently drawn from the supply roll as described. The web is held off the printing surfaces and away from the cylinders 75

when the impression is thrown off by the guides g, h, adjacent cylinder 6; and guides m, n, adjacent cylinder 7. The impression cylinder gears remain in mesh with the bed racks so that the cylinders oscillate on and during the strokes of the beds. The cutting cylinders are slightly separated so that they do not feed the web, but sever a sheet therefrom for each cycle of operations of the press.

Important practical features of the press are 10 its ability to print and deliver sheets of various length from a web, which will be a very acceptable feature to publishers who manufacture various sizes of publications. The oscillating cylinders do not have to be of any particular size, 15 other than large enough to permit printing the maximum length sheets, but I do not consider the invention in its broader aspects limited to oscillating cylinders. Mounting the cylinders on eccentric shafts I also consider novel, but the invention is not restricted to such mounting, nor to the particular sprocket and sprocket chain drives illustrated, clutches, etc., illustrated, as 20 mechanical changes and substitutions could be made by a skilled workman while retaining the 25 novel and beneficial features of my invention.

I claim:

1. A web printing press, comprising a pair of reciprocating beds, a pair of oscillating impression cylinders coacting with the bed, means for throwing the cylinders on impression at the beginning of the printing strokes of the beds, means for throwing off impression at various lengths of travel of the beds on their printing strokes and during return strokes of beds to enable sheets of 30 any desired length between minimum and maximum to be printed, and means for feeding a length of web between the cylinders and beds in accordance with the length of sheet to be printed, such means being controlled and actuated by an 35 impression cylinder.

2. A web printing press, comprising a pair of reciprocating type beds, a pair of oscillating impression cylinders coacting with the beds, means for throwing the cylinders on impression at the beginning of the printing strokes of the beds, means for throwing off impression at various 40 lengths of travel of the beds on their printing strokes and during return strokes of beds to enable sheets of any desired length between minimum and maximum to be printed, web in-feed and out-feed rolls, and means actuated by an 45 impression cylinder while on impression to operate the in-feed and out-feed rolls to feed a length of web in accordance with the length of 50 sheet to be printed.

3. In a printing press; a reciprocating bed, a cylinder cooperating with the bed, a web supply roll, an in-feed roll between the supply and cylinder, an out-feed roll beyond the cylinder; means 55 for directing a web to the in-feed roll, thence to and between the cylinder and bed, and thence to the out-feed roll; means for variably actuating the feed roll to feed any desired length of the web during the taking of an impression and for stopping the feed roll after impression is taken and during the remainder of the printing stroke of the bed and the non-printing stroke of the bed; with a pair of cutting cylinders adjacent the out-feed roll, and means for operating said cylinders to sever a sheet of the proper length from the web at each cycle of operations of the press.

4. A printing press having movable beds, cylinders cooperating with such beds, means for throwing off impression at any desired point in 70 75

- the travel of the beds during their printing stroke, a web supply, an in-feed roll between the supply and first impression cylinder, an out-feed roll adjacent the delivery end of press, means for operating the rolls to feed any desired length of web between cylinders and beds during the taking of an impression, said means being actuated and controlled by one of the impressions cylinders; with a pair of cutting cylinders adjacent the out-feed roll, and means for operating said cylinders to sever a sheet of the proper length from the web at each cycle of operations of the press.
5. A web printing press, comprising a pair of type beds, a pair of cylinders coacting with the beds, means for throwing on impression at the beginning of the printing strokes of the beds, means for throwing off impression at various lengths of travel of the beds on their printing strokes and during return strokes of beds, to enable impressions of any desired length between minimum and maximum to be printed on the web, means for feeding the web while impression is on in accordance with the length of web printed; a pair of cutting cylinders between which the printed web is forwarded, and means for rotating said cylinders to sever a sheet from the web for each cycle of operations of the press.
6. In a printing press, a reciprocating bed, a cylinder cooperating with the bed, a web feed roll, a shaft beside the feed roll, a loose gear on said shaft meshing with a gear on the cylinder, means for throwing on and off impression, means whereby when the impression is thrown on the loose gear is locked to said shaft and is disengaged therefrom when the impression is thrown off, and means for driving the feed roll from said shaft when the latter is actuated.
7. In a press as set forth in claim 6, a pair of cutting cylinders adjacent the out-feed, and means for rotating said cylinders to sever a sheet from the web for each cycle of operations of the press.
8. A web printing press, comprising a pair of reciprocating beds, a pair of oscillating impression cylinders coacting with the bed, means for throwing the cylinders on impression at the beginning of the printing strokes of the beds, means for throwing off impression at various lengths of travel of the beds on their printing strokes and during return strokes of beds to enable impressions of any desired length between minimum and maximum to be printed on the web; and means for feeding the web while impression is on, in accordance with the length of sheet printed, with a pair of cutting cylinders adjacent the out-feed roll, and means for rotating said cylinders once for each cycle of operations of the press.
9. In a printing press, a pair of reciprocating beds and cylinders, an in-feed roll, an out-feed roll, a shaft beside the out-feed roll, a loose gear on said shaft meshing with a gear on the roll; means for throwing the cylinders on and off impression; means whereby when the cylinders are on impression the loose gear is locked to said shaft and disengaged therefrom when the impression is thrown off, and means for driving the feed roll from said shaft when it is actuated; means for driving the in-feed roll from the out-feed roll, said rolls operating to feed the web while the impression is on, and stopped when the impression is off; a pair of cutting cylinders adjacent the out-feed roll, and means for rotating
- said cutting cylinders once during each cycle of operations of the press.
10. In a printing press; a reciprocating bed, a cylinder cooperating with the bed, a web supply roll, a feed roll; means for directing a web to the feed roll; means for throwing the cylinders on and off impression, an adjustable cam, means for operating the cam, means actuated by said cam for operating the throw-off means; and means for variably actuating the feed roll to feed the web for any desired length of sheet during the taking of impressions.
11. In a printing press; a reciprocating bed, a cylinder cooperating with the bed, a web supply roll, a feed roll; means for directing a web to the feed roll; means for throwing the cylinders on and off impression, including eccentric mountings for the cylinders, and adjustable cams for oscillating said eccentric mountings at proper times; and means for variably actuating the feed roll to feed the web for any desired length of sheet during the taking of impressions and for stopping the feed roll when such sheet has been printed, and during the non-printing strokes of the bed.
12. A printing press, comprising a bed, an impression cylinder coacting with the bed, means for throwing on impression at the beginning of the printing stroke of the bed, and means for throwing off impression at any desired length of travel of the bed on its printing stroke and holding it off during the remainder of the printing stroke and the return stroke of the beds, whereby sheets of any desired length between minimum and maximum can be printed; the means for throwing off impressions including eccentric mountings for the cylinders, and adjustable cams for oscillating said eccentric mountings at proper times.
13. A web printing press, comprising a pair of reciprocating type beds, a pair of oscillating impression cylinders coacting with the beds, means for throwing the cylinders on impression at the beginning of the printing stroke of the beds, and for throwing off impression at any desired point in the travel of the beds during their printing stroke and holding it off during the remainder of the printing stroke and during return stroke of beds, the means for throwing off impressions including eccentric mountings for the cylinders, and adjustable cams for oscillating said eccentric mountings at proper times; whereby sheets of any desired length between minimum and maximum can be printed; and means for feeding the web while the impression is on in accordance with the length of sheet to be printed.
14. A printing press having movable beds, cylinders cooperating with such beds, means for throwing on and off impression, a web supply, an in-feed roll between the supply and first impression cylinder, an out-feed roll adjacent the delivery end of press, means for operating the rolls to feed the web between cylinders and beds during taking of impression, said means being actuated and controlled by one of the impression cylinders, the means for throwing off impressions including eccentric mountings for the cylinders, and adjustable cams for oscillating said eccentric mountings at proper times.
15. A web printing press, comprising a pair of reciprocating type beds, a pair of oscillating impression cylinders coacting with the beds, means for throwing the cylinders on impression at the beginning of the printing stroke of the beds, means for throwing off impression at any desired

point in the travel of the beds during their printing stroke and holding it off during the remainder of the printing stroke and during return stroke of beds, an adjustable cam for operating the 5 throw off means, and means for operating the cam; whereby sheets of any desired length between minimum and maximum can be printed; and means for feeding the web while the impression is on in accordance with the length of sheet 10 to be printed.

16. In a press as set forth in claim 15, the means for throwing off impressions including eccentric mountings for the cylinders, and adjustable cams for oscillating said eccentric mountings 15 at proper times.

17. In a printing press, a reciprocating bed, an oscillating cylinder cooperating with the bed, a web supply roll, an in-feed roll between supply 20 and cylinder, an out-feed roll beyond the cylinder; means for directing a web to the in-feed roll, thence to and between cylinder and bed, thence to the out-feed roll; means whereby the out-feed roll is actuated by and from the impression cylinder only while the impression is thrown on, and 25 is stopped when the impression is thrown off; and means for throwing off impression after printing at any desired part of the printing stroke of the bed and holding off impression during the return stroke of the bed.

18. In a printing press, a pair of reciprocating beds, a pair of cylinders cooperating with the beds; a web supply roll, an in-feed roll between the supply and the first cylinder, an out-feed roll beyond the second impression cylinder; means 30 for directing a web to the in-feed roll, thence to and between first cylinder and bed, thence to and between second cylinder and bed, and thence to the out-feed roll; means for variably actuating the feed rolls to feed any desired length of the 35 web during the printing stroke of the beds and for stopping the feed rolls when an impression is taken during the remainder of the printing stroke of the beds and the non-printing stroke of the beds; and means for throwing off impression 40 after printing at any desired part of the printing stroke of the bed and holding off impression during the return stroke of the bed.

19. A printing press, comprising a bed, an impression cylinder coacting with the bed, means 45 for throwing on impression at the beginning of the printing stroke of the bed, an adjustable cam and means actuated by said cam for throwing off impression at any desired length of travel of the bed on its printing stroke and holding it off 50 during the remainder of the printing stroke and the return stroke of the beds, whereby sheets of any desired length between minimum and maximum can be printed.

20. A printing press, comprising a bed, an impression cylinder coacting with the bed, means 55 for throwing on impression at the beginning of the printing stroke of the bed, an adjustable cam and means actuated by said cam for throwing off impression at any desired length of travel of the

bed on its printing stroke and holding it off during the remainder of the printing stroke and the return stroke of the beds, whereby sheets of any desired length between minimum and maximum can be printed, and means for variably feeding 5 a web between the bed and cylinder while the impression is on in accordance with the length of sheet to be printed.

21. A web printing press, comprising a pair of reciprocating beds, a pair of impression cylinders 10 coacting with the bed, an adjustable cam, means operated by said cam for throwing the cylinders on impression at the beginning of the printing strokes of the beds and means for throwing off impression at any desired point in the travel of the beds on their printing stroke and holding it off during the remainder of the printing stroke and during return stroke of beds whereby sheets of any desired length between minimum and maximum can be printed. 15

22. A web printing press, comprising a pair of reciprocating beds, a pair of impression cylinders coacting with the bed, an adjustable cam, means 20 operated by said cam for throwing the cylinders on impression at the beginning of the printing strokes of the beds and means for throwing off impression at any desired point in the travel of the beds on their printing stroke and holding it off during the remainder of the printing stroke and during return stroke of beds whereby sheets of any desired length between minimum and maximum can be printed, and means for variably feeding the web to and between the cylinders and beds while the impression is on, in accordance 25 with the length of sheet to be printed. 30

23. A web printing press, comprising a pair of reciprocating type beds, a pair of oscillating impression cylinders coacting with the beds, an adjustable cam, means actuated by said cam for throwing the cylinders on impression at the beginning of the printing stroke of the beds, means 40 for throwing off impression at any desired point in the travel of the beds during their printing stroke and holding it off during the remainder of the printing stroke and during return stroke of beds whereby sheets of any desired length between minimum and maximum can be printed; and means for feeding the web while the impression is on in accordance with the length of sheet 45 to be printed. 50

24. A printing press having movable beds, cylinders cooperating with such beds, an adjustable cam, means operated by said cam for throwing the cylinders on and off impression at variable points in the printing stroke of the beds, a web supply, a web in-feed roll between the supply and first impression cylinder, an out-feed roll adjacent the delivery end of press, and means for operating the in-feed and out-feed rolls to feed web between the cylinders and beds during taking of impression, said means being actuated and controlled by the adjacent impression cylinder. 55 60

PAUL F. COX.
